UNITED STATES PATENT OFFICE

2,163,676

ELECTRICIAN'S TOOL

Nickolas Gizzarelli, Warren, R. I.

Application June 1, 1937, Serial No. 145,684

4 Claims. (Cl. 175—183)

This invention relates to an electrician's tool; and has for one of its objects the provision of a combined screw driver and tester which will be of such a character that when a live wire or circuit is contacted by the tip or shank of a screw driver a signal lamp will glow in the body of the screw driver even though there be no complete electrical circuit through the lamp.

Another object of the invention is the provision of an arrangement whereby the tester may be optionally used in such a way that a complete circuit may be passed through the signal lamp by attaching some lead at a convenient location upon the body of the screw driver.

15 Another object of the invention is the simplification of the assembled parts and their manner of assembly so that the device may be made inexpensively and placed on the market at a comparatively low cost.

20 Another object of the invention is the easy assembly and detachment of the parts to provide for easy replacement of the signal lamp by a fresh one should the original lamp fail to function.

25 With these and other objects in view, the invention consists of certain novel features of construction, as will be more fully described, and particularly pointed out in the appended claims.

In the accompanying drawing:

30 Fig. 1 is an elevation of the screw driver with the body thereof in section;

Fig. 2 is an elevation of the handle alone;

Fig. 3 is a section of the body alone with the signal lamp removed;

35 Fig. 4 is an elevation of the screw driver shank;

Fig. 5 is a sectional view on line 5—5 of Fig. 1;

Fig. 6 is a sectional view of a modified form of body which may be used in place of that shown in Figs. 1 and 3.

40 A screw driver has been found to be extremely useful and perhaps one of the most used instruments or tools of electricians. Testing devices are also used but usually are in some separate instrument and require the positioning of the ends of two leads in order that a circuit may be completed through the signal. I have found that a neon lamp will glow even if one of its terminals are connected to a live circuit without it being necessary to pass a current completely

45 through the lamp; and in order to utilize this characteristic of a neon lamp and also to locate the neon lamp in an extremely convenient place, I have so formulated a screw driver that the neon lamp will be in the body thereof with the

50 blade or shank of the screw driver connected to

one terminal of the neon signal lamp so that if this blade touches a live circuit the neon lamp will glow. I have also arranged in addition a terminal which may be optionally used where a bright glow in the lamp is desired, or for other uses, to place the neon lamp completely in circuit; and the following is a more detailed description of the present embodiment of this invention, illustrating the preferred means by which these advantageous results may be accomplished:

With reference to the drawing, 10 designates the hollow cylindrical tubular body of the screw driver which, as shown in Figs. 1 and 2, is made of insulating material such as fiber or some molded or plastic insulating composition such as Bakelite. The tube is provided with internal threads 11 at its upper end and 12 at its lower end and is also provided with an opening 13 of an elongated shape, as shown in Fig. 3, at a convenient location along the length of the body.

20 A handle designated generally 14 is provided with a threaded stud portion 15 to fit into the threads 11 of the body 10, while a pin 16 may extend through the diametrically opposite openings 17 and 18 in the body 10 and the hole 19 in the threaded portion 15 of the handle to lock the handle in position against turning. The end of the pin 16 is threaded as at 20 to fit into the threaded hole 18 to hold the same in position.

25 A shank 21 has a screw driver blade 22 with an enlarged head portion 23 which is threaded to fit into the threads 12 at the lower end of the body where the same is held in place by a set screw 24 having a manipulating slot 25. In the head 23 there is located threaded opening 26 for the reception of a binding screw 27.

30 A cradle 28 has its outer surface 29 shaped to fit the inner surface of the body and is recessed as at 30 to receive the neon signal lamp or bulb 31 which has terminals 32 and 33 extending therefrom. The recess is of such a shape as to snugly fit the neon lamp and hold it in position against the inner wall of the tube 10 in a location opposite the opening 13 so that the same may be viewed from the outside of the instrument. The end portion of the cradle as at 34 is shaped to prevent the tube from moving longitudinally of the cradle, while the cradle itself is held in position by the binding screw 35 passing through the wall of the tube 10 and into a threaded opening in the 35 cradle 28.

40 The terminal 32 is connected by a suitable lead 36 to the binding screw 27 thus electrically connecting the shank 21 with the signal lamp 31. The other terminal 33 of the neon signal lamp is 45

connected by lead 37 to the tubular rivet 38 with a binding post 39 threaded thereinto. This binding post has an insulating head 40 so that should one contact the post no shock will be obtained.

5. In use, this instrument of course may be used as an ordinary screw driver whenever and wherever desired. In addition, the screw driver may be used in determining a live circuit by merely touching the shank portion 21 or its blade 22 to 10 a live circuit whereupon the neon lamp will glow. Other uses are that the shank 21 may be grounded and a lead secured to the binding post 39 which may be manipulated among different wires to search for a live circuit whereupon a greater 15 glow will be had in the neon lamp because of the current passing completely through the lamp, by reason of its being put into a circuit than were but one terminal of the lamp connected to an electric current.
20. In some cases instead of using a body 10 sufficiently thick to provide threads therein I may provide a thinner body 42 and a metal ferrule 43 having threads 44 located in one end of the body and rolled over as at 45 to secure it in position, 25 the same arrangement being provided at the lower end of the tube.

The foregoing description is directed solely towards the construction illustrated, but I desire it to be understood that I reserve the privilege of resorting to all the mechanical changes to which 30 the device is susceptible, the invention being defined and limited only by the terms of the appended claims.

I claim:

35. 1. In a combination screw driver and tester, a hollow body having an opening, a cradle in the body positioned to engage the sides of a neon signal lamp and support the same in position to be viewed through said opening, a neon lamp in 40 said cradle, said cradle having a concave surface

engaging an end portion of said neon lamp, a metal shank at one end of the body, and means to electrically connect said shank and lamp.

2. In a combination screw driver and tester, a hollow body having an opening, a cradle in the body positioned to engage the sides of a neon signal lamp and support the same in position to be viewed through said opening, said cradle having a concave surface engaging an end portion of said neon lamp, a neon lamp in said cradle 5 having two terminals, a metal shank at one end of the body, means to electrically connect said shank to one of said terminals, a binding post on said body, and means to electrically connect the binding post to the other terminal. 15

3. In a combination screw driver and tester, a hollow body having an opening, a cradle in the body positioned to engage the sides of a neon signal lamp and support the same in position to be viewed through said opening, said cradle having a concave surface engaging an end portion of said neon lamp, means to removably attach said cradle to said body, a neon lamp in said cradle, a metal shank at one end of the body, and means to electrically connect said shank and 20 25 lamp.

4. In a combination screw driver and tester, a hollow body having an opening therein, a neon lamp in said body having two terminals, a cradle in the body positioned to engage the sides of said lamp and support the same, said cradle having a surface engaging an end portion of said neon lamp, a metal shank at one end of the body, means to electrically connect said shank to one 30 of said terminals, a binding post on the outer surface of said body and having the exposed surface electrically insulated, and means electrically connecting the binding post to the other terminal of said lamp. 35

NICKOLAS GIZZARELLI.
